(57) **CLAIM**

The ornamental design for a combined frequency converter and frequency converter panel, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, right side and top perspective view of a combined frequency converter and frequency converter panel in accordance with a first embodiment with no color claimed;

FIG. 2 is a front view thereof;

FIG. 3 is a back view thereof;

FIG. 4 is a bottom view thereof;

FIG. 5 is a top view thereof;

FIG. 6 is a left view thereof;

FIG. 7 is a right view thereof;

FIG. 8 is a front, right side and top perspective view of a combined frequency converter and frequency converter panel in accordance with a second embodiment having an element shown in color red;

FIG. 9 is a front view thereof;

FIG. 10 is a back view thereof;

FIG. 11 is a bottom view thereof;

FIG. 12 is a top view thereof;

FIG. 13 is a left view thereof;

FIG. 14 is a right view thereof;

(Continued)

FIG. 15 is a front, right side and top perspective view of a combined frequency converter and frequency converter panel in accordance with a third embodiment having an element shown in color red;
 FIG. 16 is a front view thereof;
 FIG. 17 is a back view thereof;
 FIG. 18 is a bottom view thereof;
 FIG. 19 is a top view thereof;
 FIG. 20 is a left view thereof;
 FIG. 21 is a right view thereof;
 FIG. 22 is a front, right side and top perspective view of a combined frequency converter and frequency converter panel in accordance with a fourth embodiment having an element shown in color red;
 FIG. 23 is a front view thereof;
 FIG. 24 is a back view thereof;
 FIG. 25 is a bottom view thereof;
 FIG. 26 is a top view thereof;
 FIG. 27 is a left view thereof; and,
 FIG. 28 is a right view thereof.
